UNITED STATES PATENT OFFICE

LOUIS E. DUPUY, OF SYRACUSE, NEW YORK, ASSIGNOR TO THE LAMSON COMPANY, OF SYRACUSE, NEW YORK, A CORPORATION OF MASSACHUSETTS

CONVEYER MECHANISM

Application filed April 23, 1930. Serial No. 446,531.

This invention relates to improvements in a conveyer mechanism and more particularly in such a mechanism embodying a traveling conveyer and a movable device which is given a movement of translation by the traveling conveyer and which thereupon performs certain predetermined operations.

An illustrative application of this invention is the operation of deflector mechanism such as is usually employed in connection with a traveling conveyer by which articles are transported for the purpose of deflecting articles from that conveyer to any desired station or second conveyer. Such mechanism includes a movable deflector arm which, when extended across the conveyer in the path of travel of the articles, deflects the articles carried and when in an inoperative position out of the path of travel, allows the articles on the conveyer to pass by the station. One means of operating the deflector arms is to provide, adjacent the conveyer, an article controlled element, usually a tab, which is actuated by the articles or by pins suitably located upon or projecting from the articles. The element when actuated causes the deflector arm to take the position determined by the element through the operation of suitably arranged mechanical mechanism.

The primary object of this invention is to provide a device for engaging the belt of an article transporting conveyer whereby the device is given a movement of translation in unison with the belt, which device is preferably brought into engagement with the belt upon the approach of certain predetermined articles.

One object of this application of the invention is to provide deflector mechanism which comprises in addition to the deflector arm and article controlled element means whereby upon actuation of the element, the deflector arm is operated by power derived from the traveling conveyer; such means, in the present embodiment, comprising a device which is caused to engage the traveling conveyer and thereupon to move simultaneously with the conveyer and operate the deflector arm. A further object of such application is to provide deflector mechanism in-

cluding a device which, when a certain article approaches the mechanism, grips the conveyer and under the impulse given to it by the conveyer causes the deflector arm to swing into the operative position whereby the article is deflected from the conveyer to a station or second conveyer.

Other objects of the invention will appear from a consideration of the following specification taken in connection with the drawings which form a part thereof and in which:

Fig. 1 is a plan view of a conveyer equipped with one embodiment of the illustrative application of this invention;

Fig. 2 is a side elevation of such conveyer;

Fig. 3 is an enlarged side elevation of the deflector;

Fig. 4 is a sectional view taken along the line 4-4 of Fig. 3;

Fig. 5 is a side elevation taken from the left of Fig. 4 illustrating the manner in which the edge of the conveyer belt is gripped;

Fig. 6 is an enlarged plan view of one form of deflector latch;

Figs. 7 and 8 are plan views similar to Fig. 1 of other embodiments of this invention;

Fig. 9 is a side elevation similar to Fig. 2 of a conveyer equipped with another embodiment.

As shown in Figs. 1 to 6 of the drawings, the conveyer A equipped with this invention, comprises upper and lower runs 10 and 11; the upper run passing between flange guide rails 12 in the usual manner, the direction of travel of the conveyer runs being designated for convenience by arrows. In the illustration of this invention I have elected to show a branch conveyer 15 which may be of any desired type and to which certain of the articles B traveling upon the conveyer A are deflected by means of the deflector mechanism.

The deflector arm 16 is fixed upon a shaft 17 carried by one side rail 12 in the usual manner and suitably supported at its base in bearings 18. Fixed upon the shaft 17 is an arm 20 which extends across the conveyer below the lower run 11 and is preferably channelular in cross section as shown in Fig. 2. A spring 21 secured at one end to the arm 20 and at the other end to a post 22 is provided to

hold the arm 20 normally in the position in which the deflector arm 16 will occupy the inoperative position shown in dotted lines in Fig. 1.

5 A rock shaft 25 is supported above and extended transversely of the conveyer A in bearings 26 carried by suitably located bars 27 parallel to the side rails 12. Fixed upon the shaft 25 is a tab 28 which extends into the path of a pin 29 fixed upon an article B as shown in Fig. 2. It will be noted that the tab 28 is comparatively narrow and will only be tripped if the pin 29 occupies a certain predetermined position upon the article. Fixed 10 upon the rock shaft 25 at one end thereof is an arm 30 connected by a link 31 with one arm 32 of a lever 33 pivotally mounted upon a pin 34. A spring 35 attached at one end to the arm 36 of the lever 33 and at the other end 15 to a bracket 37 normally holds the parts in such position that the tab 28 projects downwardly so that it will be engaged by a properly located pin 29 upon an article. Attached to the arm 36 of the lever 33 is one end of a bar 20 20 which has a horizontal reciprocation and has, adjacent its other end, a longitudinally extending slot 42. Slidable in the slot 42 is a block 43 separated from the end of the slot by a spring 44. The bar 20 as will be pointed 25 out below transmits the movement of the tab 28 to a conveyer gripping device 50. The gripping device 50 includes a sleeve 51 reciprocably carried upon a rectangular rod 52 supported at its ends by brackets 53 depending 30 from one side rail 12 of the conveyer. Secured to the sleeve 51 is a U-shaped bracket 54, by which a rock shaft 55 is supported. Carried on the rock shaft 55 is a sleeve 56 and collars 57, both sleeve and collars being fixed 35 against movement relative to the shaft by the use of set screws, the formation of irregular surfaces upon the shaft or any other suitable means. Depending from the bracket 54 is a roller 60 which as shown in Fig. 3 enters 40 the channel of the arm 20. The collars 57 are connected to or formed integral with one edge of a plate 61 which extends below the lower run 11 of the conveyer and carries a shoe 62 adapted under certain conditions to 45 engage the under face of the run 11. Fixed upon the sleeve 51 and projecting inwardly between the runs 10 and 11 is a projection 65 having a shoe 66 of rubber or similar material. As shown particularly in Figs. 4 and 5 of the drawings, one edge of the lower run 11 passes between the shoe 62 of the arm 61 and the shoe 66 of the projection 65. 50 Springs 67 secured to the collars 57 and to a block 68 carried by the sleeve 51 normally hold the plate 61 swung down out of contact with the conveyer run 11 so that its travel is not impeded in any way. Extending from the sleeve 56 is a finger 70 carrying a set screw 71 against which the plate 61 is normally brought to rest by the springs 67.

The sleeve 56 also carries an arm 75 which projects outwardly therefrom and terminates in a tip having an irregular upper surface consisting of vertically offset planes 76, 77 connected by an incline 78.

Pivotedly supported upon the block 68 is an arm 80 terminating at its lower end in a tip 81 against which the tip of the finger 75 is held by the springs 67 as shown in Fig. 3. Mounted on the arm 80 is a button 82 which passes through the slot 42 of the bar 40. Adjustably supported on the side rail 12 is a block 85 which carries a stop 86 in the path of travel of the arm 80 with the sleeve 51.

The gripping device 50 normally occupies the position shown in Fig. 3 under the urge of the spring 21 and the deflector bar 16 is in the dotted line position shown in Fig. 1. When the tab 28 is tripped by a pin 29 on an article B which is to be diverted to the branch conveyer 15 the lever 33 is actuated through the arm 30 and link 31. The bar 20 is thus drawn to the right in Fig. 2 and acts through the block 43 and button 82 to swing the arm 80 on its pivot so that the tip 81 now bears against the raised plane 76 of the finger 75. The shifting of the tip 81 depresses the finger 75 and simultaneously raises the finger 70 which, acting through screw 71, raises the plate 61 against the action of the springs 67 so that the edge of the run 11 is gripped between the shoes 62 and 66. The lower run 11 is traveling in the direction indicated by the arrow in Fig. 2 and as a result the gripping device is caused to travel to the right. This movement of the gripping device is transmitted through the arm 20 and the shaft 17 to the deflector arm 16 so that the article by which the tab 28 is tripped will be deflected onto the conveyer 15. When the gripping device has reached substantially the limit of its movement the arm 80 contacts with the button 86 causing the tip 81 to swing from engagement with the plane 76 of the finger 75 to engagement with the plane 77 as indicated in dotted lines in Fig. 3 and the springs 67 immediately act to lower the shoe 62 and release the edge of the conveyer belt so that further travel of the device ceases.

The deflector arm 16 is preferably held in the operating position by a catch of any desired type. In the present instance I have elected to show a catch 90 of the magnetic type as illustrated particularly in Fig. 6. Pivotedly mounted upon a plate 91 is a latch 92 which is normally held by a spring 93 in the dotted line position indicated on Fig. 6. The tail 94 of the latch 92 will however when the latch is swung into the full line position of Fig. 6 pass behind a striker 95. The striker 95 is carried at one end of a rod 96 suitably supported by spaced brackets 97 and secured at its other end in a yoke 98 formed at the end of a piston 99 of a solenoid

100. Fixed on the rod 96 is a collar 101, between which and one of the brackets 97 is provided a coil spring 102 to hold the bar normally advanced.

5 In the branch conveyer 15 is mounted a circuit maker 105, the arm 106 of which is tripped by each article as it travels down the conveyer 15. The tripping of the circuit maker 105 acts in the usual well known manner through a circuit 107 to energize the solenoid 100 thus causing the piston 99 to be retracted and the striker 95 to release the tail 94 of the latch 92.

10 The normal position of the catch mechanism is as shown in dotted lines in Fig. 6. When the deflector arm 16 is swung across the path of the conveyer by the mechanism previously described, a pin 108 carried by the deflector arm enters the notch 109 of the 20 latch 92 and swings it from the dotted line position of Fig. 6 past the striker 95 into the full line position there shown. The deflector arm 16 is thus held rigidly across the path of travel of the conveyer but as soon as 25 the arm 106 of the circuit maker 105 is tripped the solenoid 100 retracts the rod 96 releasing the latch 92 and allowing the deflector arm and the gripping device to be returned by the spring 21 to the normal 30 position.

35 The embodiments shown in Figs. 7 and 8 differ from that previously described in that the gripping device 50^a is caused to engage one edge of the upper run of the conveyer rather than the lower run. The mechanism employed therein is the same as that illustrated in detail in the other embodiment with the exception that the sleeve 51^a reciprocates upon a bar 52^a which is substituted for a portion 40 of the side rail 12 and a suitably formed guard 110 is provided to prevent the articles from coming into contact with the gripping device.

45 Referring to Fig. 7 the deflector arm 116 is pivotally mounted upon a shaft 117 from which shaft extends an arm 118 connected by a link 119 with an arm 120 on a shaft 121. Fixed upon the shaft 121 is an arm 122 of substantially the same construction as the 50 bar 20 in the first embodiment. It will be understood that the gripping device 50^a is connected to the arm 122 and is actuated by the article through a tab (not shown) in the manner previously described. The edge of the upper run 10 of the conveyer A is then engaged by the gripping device which travels to the right as shown in Fig. 7 and causes the deflector arm 116 to shift from the inoperative dotted line position to the operative full line position in which it is held by a catch mechanism 90^a of any desired type and deflects articles to the branch conveyer 15^a. When the gripping device 50^a reaches 60 the limit of its travel, the arm 80^a is engaged

by an adjustable stop 85^a and the run is released.

In Fig. 8 the deflector arm 116^a is pivotally mounted on a shaft 117^a, which shaft carries an arm 118^a connected by a link 119^a with an arm 120^a on a shaft 121^a. Fixed on the shaft 121^a is an arm 122^a which is operated by the gripping device 50^a in the manner previously described under the control of the tab 28^a. The arm 116^a is held in the operative position by a catch mechanism 90^a and thus deflects articles to the branch conveyer 15^a.

20 In Fig. 9 is shown an embodiment of the invention in which the deflector is actuated by the engagement of the gripping with the edge of a supplementary belt movable in relation with the transporting conveyer. The features of this embodiment which are in common with the embodiment of the invention shown in Figs. 1 and 2 will not be described in detail and will be designated by the primes of the reference characters there used.

25 Mounted between the rims 10' and 11' of the conveyer A' is a continuous belt 150 supported at its ends upon rollers 151. Suitable idler rollers 152 over which the upper rim of the belt 150 passes coat with the rollers 151 to hold the belt in contact with the conveyer A' so that it travels in unison therewith. The normal plane of travel of the conveyer A is shown by the rollers 153 to be below the plane determined by the rollers 150 and 153. The surfaces of the belt 150 and conveyer A' are thus in contact, which contact is further increased by the weight of the article travelling thereover so that any danger of slippage is practically eliminated. The deflector arm 16' is fixed upon the shaft 17' from which projects the arm 20' that is actuated by the gripping device 50'. The device 50' is caused to engage one edge of the belt 150 when the tab 28' is tripped by the approaching article.

30 The main feature of this invention is the provision of a gripping device which engages the traveling conveyer or a belt movable in relation therewith and which is here shown as employed to operate the deflector arm quickly and silently. Other uses for the device might be provided and hence I am not limited to the particular use set up in the illustrated embodiments. In the drawings the article transported by the conveyer is a carrier of the type set forth in the Cowley Patent 1,712,872 dated May 14, 1929, but it will be understood that I am not limited thereto and that the elements 28, 28^a 35 may be of any desired construction and operated in any desired manner. Moreover I am not limited to the particular form and arrangement of the various elements disclosed since others might be employed without de- 40

parting from the spirit and scope of the invention as set forth in the following claims.

I claim:

1. The combination with a traveling conveyer of a movable deflector arm which in one position is inoperative and in another position is operative to deflect from the conveyer articles carried thereby and means for moving the deflector arm from the inoperative to the operative position, said means including a tab adjacent said conveyer and adapted to be actuated by predetermined articles and a device which engages the conveyer upon the actuation of the tab whereby the movement of the conveyer is transmitted to the deflector arm.
2. The combination with a traveling conveyer of a movable deflector arm which in one position is inoperative and in another position is operative to deflect from the conveyer articles carried thereby and means for moving the deflector arm from the inoperative to the operative position, said means including a tab adjacent said conveyer and adapted to be actuated by predetermined articles, a device which, when the tab is actuated, grips the edge of the conveyer and is shifted thereby and means for transmitting the movement of the device to the deflector arm and operating it.
3. The combination with a traveling conveyer of a movable deflector arm which in one position is inoperative and in another position is operative to deflect from the conveyer articles carried thereby and means for moving the deflector arm from the inoperative to the operative position, said means including a device which grips one edge of the conveyer whereby the movement thereby is transmitted to the deflector arm.
4. The combination with a traveling conveyer of a movable deflector arm which in one position is inoperative and in another position is operative to deflect from the conveyer articles carried thereby and means for moving the deflector arm from the inoperative to the operative position, said means including a device which grips one edge of the conveyer and means actuated by certain of said articles for operating said device whereby the movement of the conveyer is transmitted to the deflector arm.
5. The combination with a belt conveyer having an upper and a lower run on one of which runs articles are transported, of a deflector arm movable relative to the article transporting run, which arm in an inoperative position allows the articles to pass freely along the conveyer and in the operative position deflects articles from the conveyer, means associated with the transporting run of the conveyer and adapted to be actuated by certain articles transported thereby, a device for gripping the edge of the other run of the conveyer when the means are actuated and

connections between the device and the deflector arm for causing said arm to move into the operative position and deflect the article, by which the means is actuated.

6. The combination with a belt conveyer having an upper and a lower run on one of which runs articles are transported, of a deflector arm movable relative to the article transporting run, a device for engaging the other run of the conveyer for actuating said deflector arm and means actuated by an article transported by the conveyer for bringing said device into engagement with the conveyer run.

7. The combination with a belt conveyer of a device for engaging the conveyer, said device comprising a sleeve mounted for reciprocation parallel to the conveyer, a shoe fixed upon said sleeve and located at one side of the belt, a second shoe pivotally supported upon said sleeve and located at the other side of said belt and a movable arm carried by said sleeve which in its movement causes said second shoe to swing into contact with the belt and grip the latter against the fixed shoe whereupon said sleeve is caused to travel in unison with the conveyer, and means actuated by articles transported by the conveyer for operating said arm.

8. The combination with a belt conveyer of a device for engaging the conveyer, said device comprising a sleeve mounted for reciprocation parallel to the conveyer, a shoe fixed upon said sleeve and located at one side of the belt, a second shoe pivotally supported upon said sleeve and located at the other side of said belt and a movable arm carried by said sleeve which in its movement causes said second shoe to swing into contact with the belt and grip the latter against the fixed shoe whereupon said sleeve is caused to travel in unison with the conveyer, means actuated by articles transported by the conveyer, for moving the arm into shoe operating position and means for moving the arm to release the shoe after the sleeve has traveled a predetermined distance.

9. The combination with a belt conveyer of a device for engaging the conveyer, said device comprising a sleeve mounted for reciprocation parallel to the conveyer, a shoe fixed upon said sleeve and located at one side of the belt, a second shoe pivotally supported upon said sleeve and located at the other side of said belt and a movable arm carried by said sleeve which in its movement causes said second shoe to swing into contact with the belt and grip the latter against the fixed shoe whereupon said sleeve is caused to travel in unison with the conveyer, means actuated by articles transported by the conveyer for moving the arm into shoe operating position and a stop with which the arm is brought into contact upon the travel of the sleeve

whereby the arm is moved to release the shoe from engagement with the belt.

10. The combination with a belt conveyer, of movable means associated therewith, a movable device which in one position is actuated by the conveyer, means for transmitting the movement of the device to said movable means, and means tripped by an article transported upon the conveyer for moving the device into the actuating position whereupon the device is actuated by the conveyer and its movement is transmitted to the movable means.

11. The combination with a traveling conveyer of a movable deflector arm which in one position is inoperative and in another position is operative to deflect from the conveyer articles carried thereby and means for moving the deflector arm from the inoperative to the operative position, said means including a device normally out of contact with the conveyer and means actuated by articles upon the conveyer for causing the device to engage the conveyer whereby the movement thereof is transmitted to the deflector arm.

12. The combination with a traveling conveyer of a movable deflector arm which in one position is inoperative and in another position is operative to deflect from the conveyer articles carried thereby, means including mechanism normally out of contact with the conveyer, which mechanism when in contact therewith is translated thereby for moving the deflector arm from the inoperative to the operative position, and means actuated by a predetermined article on the conveyer for causing said mechanism to contact with the conveyer.

13. Conveying apparatus comprising a belt conveyer, a deflector movable across the belt conveyer for deflecting articles therefrom, means tending to hold the deflector alongside the belt conveyer, belt gripping mechanism engageable with the belt conveyer for movement therewith, control means for effecting engagement of the belt gripping mechanism with the belt conveyer, and means for transmitting motion from the belt gripping mechanism during travel thereof to the deflector for moving the latter across the conveyer.

14. The combination with a belt conveyer having an upper and a lower run on one of which runs articles are transported, of a deflector arm movable relative to the article transporting run and means for engaging the other run of the conveyer for actuating said deflector arm.

15. The combination with a belt conveyer of a device for engaging the conveyer, said device comprising a sleeve mounted for reciprocation parallel to the conveyer, a shoe fixed upon said sleeve and located at one side of the belt, a second shoe pivotally supported

upon said sleeve and located at the other side of said belt and a movable arm carried by said sleeve which, in its movement, causes said second shoe to swing into contact with the belt and grip the latter against the fixed shoe, whereupon said sleeve is caused to travel in unison with the conveyer.

16. The combination with a belt conveyer of a device for engaging the conveyer, said device comprising a sleeve-mounted for reciprocation parallel to the conveyer, a shoe fixed upon said sleeve and located at one side of the belt, a second shoe pivotally supported upon said sleeve and located at the other side of said belt, and a movable arm carried by said sleeve which in its movement causes said second shoe to swing into contact with the belt and grip the latter against the fixed shoe, whereupon said sleeve is caused to travel in unison with the conveyer, and means for operating said arm.

17. The combination with a belt conveyer of a device for engaging the conveyer, said device comprising a sleeve mounted for reciprocation parallel to the conveyer, a shoe fixed upon said sleeve and located at one side of the belt, a second shoe pivotally supported upon said sleeve and located at the other side of said belt, and a movable arm carried by said sleeve which in its movement causes said second shoe to swing into contact with the belt and grip the latter against the fixed shoe, whereupon said sleeve is caused to travel in unison with the conveyer, means for moving the arm into shoe operating position and means for moving the arm to release the shoe after the sleeve has traveled a predetermined distance.

18. The combination with a belt conveyer of a device for engaging the conveyer, said device comprising a sleeve mounted for reciprocation parallel to the conveyer, a shoe fixed upon said sleeve and located at one side of the belt, a second shoe pivotally supported upon said sleeve and located at the other side of said belt and a movable arm carried by said sleeve which, in its movement, causes said second shoe to swing into contact with the belt and grip the latter against the fixed shoe, whereupon said sleeve is caused to travel in unison with the conveyer, means for moving the arm into shoe operating position and a stop with which the arm is brought into contact upon the travel of the sleeve, whereby the arm is moved to release the shoe from engagement with the belt.

Signed by me at Syracuse, New York, this 16th day of April, 1930.

LOUIS E. DUPUY.
